COUPLING MEANS

Jakob R. Frei, Sidney, N. Y., assignor to Bendix
Aviation Corporation, New York, N. Y., a cor-
poration of Delaware

Application May 14, 1943, Serial No. 487,025

2 Claims. (Cl. 64—24)

1

This invention relates to coupling means for drivably connecting rotatable parts and more particularly to apparatus whereby both permanent and automatic adjustments of the angular relation of said parts may be readily effected.

One of the objects of the present invention is to provide novel means whereby two rotating elements may be mechanically coupled to each other in such a manner as to permit angular adjustment of one of said elements relative to the other.

Another object of the invention is to provide novel coupling means of the above character which are adapted to be automatically operated as a function of an operating characteristic of an engine, such as the speed or load thereof.

A further object is to provide novel coupling means of the above character which is reliable and efficient and which is compact and rugged.

Still another object is to provide novel means adapted for automatically effecting adjustments in the timing of the sparks in the ignition system of an internal combustion engine.

The above and further objects and novel features of the invention will more fully appear from the following detailed description when the same is read in connection with the accompanying drawings. It is to be expressly understood, however, that the drawings are for the purpose of illustration only and are not intended as a definition of the limits of the invention, reference for this latter purpose being had primarily to the appended claims.

In the drawings, wherein like reference characters refer to like parts throughout the several views,

Fig. 1 is a side elevation, mostly in section and with parts broken away, illustrating one form of device embodying the invention; and,

Figs. 2 and 3 are similar views showing modified forms of devices embodying the invention.

Three embodiments of the invention are illustrated in the accompanying drawings, by way of example, in the form of means for adjustably coupling a rotor of a magneto or a shaft carrying a circuit breaker cam to a driving member of an engine or other prime mover. As shown, a shaft 5 has one end thereof journaled in a suitable bearing 6 mounted in a casing 7. Novel means, including fluid pressure actuated means, are provided in a removable extension 8 of the casing for drivably connecting shaft 5 to an engine member (not shown).

In the form shown in Fig. 1, the novel coupling means for connecting shaft 5 to a driving

member are housed in casing extension 8 and comprise a sleeve 9 which has a splined connection with a portion of driven shaft 5 and hence rotates therewith. Sleeve 9 is preferably surrounded by a suitable oil sealing means 10 mounted in a partition member 11 which divides casing 7, 8 into separate fluid-tight compartments. The oil seal may be of the type commercially known as a "Gits" seal. Sleeve 9 is preferably adjustably connected with a second sleeve 12 that loosely surrounds a smooth portion of shaft 5 by adjustable coupling means of the character illustrated in Spengler U. S. Patent No. 2,266,283. The left end of sleeve 9, as viewed in the drawings, is provided with a plurality of ratchet teeth 13 which mesh with a like number of ratchet teeth on one face of a ring 14 that loosely surrounds shaft 5 and is adapted for angular movement relative thereto. The adjacent or right-hand end of sleeve 12 has a plurality of ratchet teeth 15, preferably one more or less than the number on sleeve 9, which mesh with a like number of ratchet teeth on the adjacent face of ring 14. One set of said ratchet teeth is so arranged that the flat, axially-extending faces thereof transmit torque for one direction of rotation while the teeth of the other set are so arranged that the corresponding faces thereof transmit torque for the other direction of rotation. The purpose of this arrangement will clearly appear hereafter in the description of the operation of the device.

Sleeve 12 is drivably connected with a driving sleeve 16 by means of a coupling sleeve 17. The latter has internal splines at each end thereof which mesh with external splines 18 and 19 on sleeves 16 and 12, respectively. Either one or both of these last mentioned sets of splines may be spiral. As shown, splines 19 are spiral and splines 18 extend in the direction of the axis of the shaft. Driving sleeve 16 is freely mounted on a spacer sleeve 20, which is in turn freely mounted on shaft 5 for a purpose to appear hereafter. The outer end of sleeve 16 extends beyond casing extension 8 and is adapted to mesh with a driving member of an engine (not shown) in any suitable manner well understood in the art. Extension 8 is provided with ears 8' by means of which casing 7, 8 may be secured to an engine casing.

It will be noted that the inner end of spacer sleeve 20 butts against sleeve 12 and a retainer for a coil spring 21 formed by a pair of oppositely disposed cupped washers 22 and 23 is interposed between the outer end of said spacer sleeve and

a retaining washer 24. The latter is held in place by a nut 25 threaded onto the end of shaft 5, the diameter of said washer being sufficient to hold driving sleeve 16 in its assembled position. Sleeve 16 is thus interposed between the end of sleeve 12 and washer 24 with sufficient clearance to permit free angular movement of sleeve 16. The pressure exerted by nut 25 is transmitted through washer 24, retainer 22, 23 and spacer sleeve 20 to sleeve 12 to thereby positively maintain the sets of ratchet teeth 13 and 15 in positive mesh so that parts 9, 12 and 14 rotate, in effect, as a single part.

When it is desired to make an adjustment in the angular relationship of driving sleeve 16 and driven shaft 5 through the medium of the ratchet coupling, it is only necessary to loosen nut 25 sufficiently to permit the ratchet teeth of one of sets 13 or 15 to slide over one another. Although the ratchet teeth will be yieldably held in mesh by spring 21 when nut 25 is loosened, movement of either sleeve 16 or driven shaft 5 in one direction will cause one set of the ratchet teeth to skip and permit movement of ring 14 relative to one of the sleeves 9 or 12, whereas movement in the other direction causes the other set of ratchet teeth to skip. Accordingly, by angularly reciprocating shaft 5, for example, first in one direction and then in the other an amount equal approximately to the pitch of the ratchet teeth, very small adjustments in the angular relationship of the driving and driven parts 16 and 5 may be effected, as is more fully described in said Spengler patent referred to above wherein the ratchet coupling per se is claimed.

It will be apparent that if either one or both of the sets of splines 18 or 19 is spiraled, axial movement of coupling sleeve 17 will cause relative angular movement of sleeves 12 and 16 and, hence, relative angular movement of sleeve 16 and shaft 5 which is directly connected to sleeve 12. The desired axial movement of coupling sleeve 17 may be effected in a novel manner and by novel means to be next described. As illustrated, said novel means comprises a ball bearing 26 or other suitable bearing mounted on a central portion of sleeve 17, the inner race thereof being held in place by a retaining ring 27. The outer race of said bearing is engaged at one end by a cup-like member 28 and at the other end by a ring 29, which is in turn engaged by a heavy coil spring 30 that is installed under initial compression. The opposite end of said spring rests against partition 11 and tends to maintain sleeve 17 in its extreme left-hand position, said position being determined by an abutment 31 in casing member 8 which serves as a stop for member 28.

Movement of coupling sleeve 17 against the pressure of spring 30 is preferably effected by a plurality of fluid pressure operated pistons 32, only one of which is shown. Piston 32 is adapted to be reciprocated in a cylinder 33, which is fitted into a suitable recess in casing member 8. A light compression spring 34 normally holds piston 32 against an arm 35 which extends radially from member 28. This spring holds the parts in ready position and obviates any lag in operation or rattling.

The interior of cylinder 33 may be connected with any suitable source of fluid pressure (not shown) through an opening 36 in casing member 8 or other suitable inlet. The pressure exerted on piston 32 by the liquid or gaseous pressure from said source may be made to depend upon

the speed, load, oil pressure, or other operating characteristic of an engine or other prime mover in any of many ways well-known in the art so that movement of coupling sleeve 17 and, hence, the angular adjustment of the connected parts during rotation thereof may be automatically effected as a function of the speed, load, etc., of the prime mover. It will also be understood that the pressure to cylinder 33 may be manually controlled in any suitable manner at the will of an operator. A plurality of fluid pressure devices 32, 33 may be equally spaced about shaft 5 to thereby obviate any tendency toward tilting member 28 when the pistons exert a pressure thereon.

In the operation of the above-described apparatus, sleeve 16 is driven by the engine or other prime mover and the rotary motion thereof is transmitted through splines 18 to coupling sleeve 17 and thence through spiral splines 19 to sleeve 12. As pointed out above, sleeve 12, ring 14 and sleeve 9 rotate as a unit with shaft 5. Relatively frictionless rotation of sleeve 17 relative to member 28 and spring 30 is permitted by the roller or ball thrust bearing 26. The parts are held by said spring in the axial positions illustrated until the fluid pressure in cylinder 33 is sufficient to overcome the spring pressure. The fluid pressure may either be continuous and increased slowly to gradually overcome the pressure of the spring or it may be controlled in any other suitable manner to get the desired angular adjustment at the proper time or times. For example, the fluid pressure may be controlled so as to cause the parts to move rapidly to their extreme right-hand position or to cause the same to move slowly or in stages through a series of intermediate positions. Movement of sleeve 17 to the right, as viewed in the drawings, will cause shaft 5 to be retarded or advanced relative to sleeve 16; depending upon the direction of the spiral splines 19. By thus advancing or retarding the shaft and, hence, the magneto rotor or circuit breaker cam mounted on the shaft, the timing of the sparks in an ignition system may be automatically varied.

The modification shown in Fig. 2 differs from the embodiment described above only in that a modified hydraulic or fluid pressure means is provided for shifting coupling sleeve 17 during operation of the unit. Accordingly, all parts of the coupling unit of Fig. 2 which are the same as or similar to parts of the first embodiment are designated by the same reference characters and will not be again described.

In the embodiment of Fig. 2, member 38 corresponds with member 28 of Fig. 1 and also serves as an annular piston of the hydraulic actuating means. The outer periphery of member 38 slidably engages the internal walls of a cylinder 39 which may be integral with casing 8 or removably secured therein, as illustrated, by set screws 40. A cylindrical extension 41 is formed integrally with member 38 and slidably extends through an opening 42 in the end of casing member 8. An annular expandable chamber 43 is thus formed for receiving a fluid under pressure, said chamber being bounded by the outer wall of cylindrical extension 41, the inner wall of cylinder 39 and the adjacent radially-extending faces of casing 8 and member 38. Fluid pressure, either liquid or gaseous, may be directed into chamber 43 from any suitable source through one or more passages 44 in casing member 8.

When sufficient pressure is exerted on piston 38 to overcome the effort exerted by spring 30, there will be no tendency to tilt and, hence, bind

the axially movable parts since the fluid pressure is applied equally around the entire face of the annular piston. If desired, suitable packing material 45 may be provided between extension 41 and the walls of opening 42 in casing member 8 as insurance against leakage from chamber 43. Said packing material may be retained in position by a gland ring 46 which is shown secured to casing 8 by set screws 47. Piston rings may also be employed on the periphery of member 38 if necessary to avoid excessive leakage.

In the modification illustrated in Fig. 3 of the drawings, the fluid pressure or hydraulic shifting means of Fig. 1 are shown and designated by the same numerals. It will be understood, however, that the single cylinder fluid pressure means of Fig. 2 might be used in this embodiment. The modified form of the invention shown in Fig. 3 differs from that shown in Fig. 1 in that the adjustable coupling means 13, 14, 15 is eliminated and spiral splines 19 are cut on an enlarged portion 12' of shaft 5' instead of on a sleeve corresponding to sleeve 12.

Splines 19 mesh with corresponding spiral splines on coupling sleeve 17 and internal splines 17' at the outer end of said sleeve mesh with a set of external splines 18a on the inner end of driving sleeve 16' which is loosely mounted on shaft 5' between nut 25 and the enlarged portion 12' of the shaft. On the outer exposed end of sleeve 16' is a set of splines 18b which mesh with a suitable drive member (not shown) of a prime mover, such as an internal combustion engine. The number and, hence, the angular extent of each of the splines 18b is different from the number and angular extent of splines 18a so that by changing the meshing relation of splines 18a and 17', small angular adjustments which are fixed during operation may be effected in the angular relationship of shaft 5' and the driving member of the prime mover with which splines 18b are meshed. In one suitable embodiment of the invention, sleeve 16' has seventeen splines 18b and twenty-four splines 18a. The splines of each set are preferably equally spaced and of equal angular extent.

If additional fixed or permanent adjustment is necessary, the bolt holes 8a in ears 8' of the mounting flange (shown only in Figs. 1 and 2) may be arcuate in shape with the center of the arc on the axis of rotation of shaft 5 or 5', thereby permitting some broadly angular movement of casing 7, 8 around the shaft when the latter is drivably connected to the prime mover. Except for the manner in which the fixed or permanent angular adjustments are effected, the operation of the embodiment of Fig. 3 is the same as described above in connection with Fig. 1. The same numerals are employed in these two figures to designate like parts.

There is thus provided novel apparatus adapted for coupling rotatable parts together whereby fixed, small, angular adjustments thereof may be readily accomplished and whereby temporary angular adjustments of said parts may be effected during rotation thereof as a function of some variable characteristics or condition, such as the speed of an engine, for example. Additionally, said coupling apparatus is adapted to be compactly arranged in a small space but is nevertheless sturdy and reliable. The device comprehended is also adapted for either automatic or manual control insofar as adjustments during operation are concerned.

Although only three embodiments of the invention have been illustrated and described in detail, it is to be expressly understood that the same is not limited thereto since it will now be apparent to those skilled in the art that variations, particularly in the design and arrangement of parts illustrated, may be made without departing from the spirit and scope of the invention. For a definition of the limits of the invention, reference is had primarily to the appended claims.

What is claimed is:

1. In apparatus of the class described, a pair of rotatable members having external splines thereon, the splines on at least one of said members being spiral, a coupling sleeve having two sets of internal splines operatively meshing with said external splines, an annular element surrounding said coupling sleeve, means, such as a roller or ball thrust bearing, for connecting said sleeve to said element for axial movement therewith and substantially frictionless rotary movement relative thereto, yieldable means for normally holding said element in a predetermined axial position, and fluid pressure operated means for moving said element axially against the efforts of said yieldable means, said fluid pressure operated means comprising a plurality of cylinders equally spaced around said element and a piston reciprocably mounted in each of said cylinders and operatively associated with said element.
2. In apparatus of the class described, a rotatable shaft, a plurality of spiral splines connected with said shaft for rotation therewith, an externally splined sleeve loosely mounted on said shaft for angular movement relative thereto, a coupling sleeve having internal splines meshing with said spiral splines and the splines on said first-named sleeve, an annular element surrounding said coupling sleeve, means for connecting said coupling sleeve to said element for axial movement therewith and relatively frictionless rotary movement relative thereto, yieldable means for normally holding said element in a predetermined axial position, and fluid pressure operated means for moving said element axially against the efforts of said yieldable means, said fluid pressure operated means comprising a plurality of cylinders spaced around said element and a piston reciprocably mounted in each of said cylinders and operatively associated with said element.
